DRAFT DAMPER

Forrest L. Hitchcock, Indianapolis, Ind., assignor
to FurnasSlave, Inc.

Application May 14, 1934, Serial No. 725,558

1 Claim. (Cl. 236—96)

This invention relates to the art of dampers and particularly to a damper adapted to be incorporated in a smokestack leading from a furnace to a chimney. The invention may be employed with a furnace having natural forced or induced draft. The invention further relates to means for closing the damper when a normal draft is desired and automatically opening the damper to check the fire.

10 A primary object of the invention is to conserve heat and in this regard, the structure embodying the invention is so designed that when the draft is cut off from the furnace, the heat within the chimney will be preserved so that the chimney or stack will not be cold when the draft is to be resumed through the furnace. A further primary object of the invention is to prevent the drawing out of warm air from the furnace room when the draft through the furnace is interrupted by the damper so that the operation of the damper will not induce a flow of cold air into the building or room wherein the furnace is placed.

Other advantages and objects of the invention such as the control of the damper through a very simple operating mechanism and cheapness of construction, will become apparent to those skilled in the art by the following description of one particular form of the invention as illustrated by the accompanying drawings, in which

Fig. 1 is an elevation of a structure embodying my invention;

Fig. 2, a vertical transverse section on the line 2—2 in Fig. 1 on an enlarged scale;

Fig. 3, a top plan view of the damper structure;

Fig. 4, a side elevation, and

Fig. 5, a detail in vertical section on the line 5—5 of Fig. 3.

Like characters of reference indicate like parts throughout the several views in the drawings.

The invention is particularly adapted to be employed in connection with some sort of an automatic burner or stoker herein generally designated by the numeral 10, Fig. 1, which is here shown as being connected with a warm air furnace 11 having a smoke pipe 12 leading to a chimney or stack 13. The smoke pipe 12 is provided with an opening, here shown as being on its upper side, about which opening is placed a housing 14 having its upper edges terminating in a common horizontal plane with a finish strip 15 therearound, here shown as in the form of an angle iron.

55 A shaft 16 is rockably carried transversely across the housing 15 near the upper side there-

of and toward the end adjacent the furnace. Fixed to the shaft 16 is a plate 17 formed to fit freely within the housing so that it may swing downwardly to extend across the pipe 12 therewithin in some such position as indicated in Fig. 4. The length of the plate 17 is made to be such that when in the downwardly hanging position, a passage will be left thereunder so as to permit gases to escape from the furnace 11 through the pipe 12 and into the stack 13 although the major movement of gases and air therethrough is retarded by the presence of the plate 17. This plate 17 is further formed to be of that shape and proportion to have the plate 17 fit closely against the under side of the inturned leg of the angle iron 15 when the shaft 16 is rocked to swing the plate 17 upwardly thereagainst.

A crank 18 is fixed to one end of the shaft 16 on the outer side of the housing 14 as a means of rocking the shaft 16. A rigid connecting link 19 is pivotally secured to the outer end of the crank 18 and hangs downwardly to be pivotally connected to an end of a bar 20. The other end of this bar 20 is securely anchored to a fitting 21 which is secured in place along the side of the pipe 12. This bar 20 is a bimetallic member so that when heat is applied thereto it will become distorted to bend out of a straight line, the bar normally being straight. The fitting 21 is herein shown as being mounted on a tube 32 which would be employed to carry a thermostat (not shown) for control of a stoker 10. The fitting 21 is preferably of an adjustable nature so that the position of the bar 20 may be adjusted in relation to the swinging travel of the crank 18 so that the desired degree of travel of the plate 17 may be produced. The bar 20 carries an electrical heating element 22 therearound of a suitable resistance so as to set up a heating effect on the bar 20 when current flows through the element. The fitting 21 is adjusted initially to the position indicated in Figs. 3 and 4 to have the bar 20 elastically pulling downwardly on the link 19 so as to rock the plate 17 to its closed or lowermost position. This position is determined by the adjustable screw 23 which extends through the angle iron 15 to have its end abut the plate 17 from the under side thereof.

When an electrical current is sent through the element 22, sufficient heat is generated therein to cause the bar 20 to warp or bend upwardly (the bar 20 being so turned as to have its motion in that direction) as indicated in Fig. 4 by the dash lines, so that the link 19 will be pushed upwardly to rock the crank 18 and in turn rock the shaft 16

so as to lift the plate 17 to its upper position against the under side of the overturned leg of the angle iron 15. In this position the normal draft through the pipe 12 may be had without 5 interference of any damper members. Now when the heat produced by the furnace 11 is sufficient, the electrical current flowing through the element 22 is interrupted by any suitable means (not here shown), which means does not form a part of this 10 particular invention. In this regard reference is had to my Patent No. 2,041,833, issued May 26, 1936 as relating to a control system. Upon the interruption of this flow of current, the bimetallic member 20 will then start to cool and return to 15 its normal straight position so as to rock the plate 17 around to the reduced draft position again.

When the plate 17 is in this reduced draft position, air may enter through the open upper 20 end of the housing 14 and flow into the pipe 12 and on into the stack 13. This flow of air, however, may be objectionable in that it would ordinarily tend to pull warm air out of the room and even adjoining rooms wherein the furnace is located 25 which would cause a reduction in temperature and loss of heat therein. Not only would such a condition arise but also the air entering through the top of the housing 14 would have a tendency to reduce the interior temperature of 30 the stack 13 so that when the plate 17 was again rocked to the full draft position, the draft would not then be of that intensity which prevailed just prior to the shifting of the plate 17 to the closed draft position since the reduction of temperature 35 in the stack 13 would tend to reduce the movement of air therethrough. It is desirable to maintain the draft through the stack 13 at the same rate of flow so as to give a better regulation of fire control in the furnace 11.

40 Therefore I preferably include in my damper construction an auxiliary plate 24 which is also secured to the shaft 16 to be rocked therewith. The plate 24 is shaped to fit down snugly over the top side of the angle iron 15 and is so positioned 45 on the shaft 16 that it will be in contact with that angle iron 15 when the plate 17 is rocked to the no-draft position. In this way the flow of air into the housing 14 is completely cut off when the draft through the pipe 12 from the 50 furnace 11 is at the minimum flow thereby conserving heat not only within the room but also within the stack 13. Preferably a counter-balance weight 25 is employed to balance the weight of the plates 17 and 24 so that the bar 20 will 55 not have to carry the weight thereof.

The bimetallic bar 20 is elastic and thereby provides a yielding and cushioning member in the operating system which is particularly effective when the plates 17 and 24 reach their closing 60 positions. When the plate 17 is shifted to its

upper position so as to give full draft through the pipe 12, the elasticity of the bar 20 permits the plate 17 to drop downwardly slightly under sudden reductions in pressure thereunder as may be induced in the pipe 12 by gusts of wind 5 across the top of the stack 13. This action helps to maintain a constant draft through the furnace 11 practically unaffected by these gusts of wind and also by variations in draft set up by differences in out-of-door temperatures and also by 10 tall stacks giving more than a predetermined required maximum draft.

In order to protect the element 22 about the bar 20, I preferably employ a housing 26 there-over in spaced relation. By use of the bimetallic 15 bar 20 with the heating element 22 therearound, I am able to effect a shifting action of the damper members without having to employ motors or solenoids heretofore considered to be necessary for such controls. By use of my structure, a 20 silent and effective operation is secured with perfect reliability.

It is to be noted that by employment of the combination of plates 17 and 24, the closure of one does not set up a draft resistance to the 25 opening of the other. Also, the plate 17 closes elastically against the gas flow from the furnace, permitting those gases to lift the plate 17 to escape in case of a hot fire. The area of the opening through the pipe and housing is such that 30 draft increases on the forward or stack side of the plate 17 do not affect the draft therebehind as determined by the position of the plate 17.

While I have herein shown and described my invention in the one best form as now known to me, 35 it is obvious that structural changes may be made without departing from the spirit of the invention and I therefore do not desire to be limited to that precise form beyond the limitations as may be imposed by the following claim.

I claim:

The combination with a smoke-pipe leading from a furnace to a stack, said pipe having an air inlet, a rock shaft mounted transversely across the inlet, a damper plate fixed to the 45 shaft to swing down into the smoke pipe, an auxiliary damper plate fixed to the shaft at an angle to the first damper plate to swing to close said inlet as said first damper plate swings into the smoke pipe, a set screw adjustable toward and 50 from the first damper plate to determine the maximum movement of said plate into the smoke pipe, a crank fixed to the rock shaft, a bimetallic bar formed of a plurality of strips having different coefficients of expansion pivotally attached to 55 the crank, a fitting to which the other end of the bar is attached and means for rotatably adjusting the fitting to adjust the position of the bar in relation to the position of the crank.

FORREST L. HITCHCOCK. 60
